UNITED STATES PATENT OFFICE.

JOSEPH H. KAISER AND ANDREW B. LEDWITH, OF BROWNSVILLE, PENNSYLVANIA.

ELECTRIC TIME-LOCK.

SPECIFICATION forming part of Letters Patent No. 447,409, dated March 3, 1891.

Application filed May 15, 1890. Serial No. 351,932. (No model.)

To all whom it may concern:

Be it known that we, JOSEPH H. KAISER and ANDREW B. LEDWITH, citizens of the United States, residing at Brownsville, in the county 5 of Fayette and State of Pennsylvania, have invented certain new and useful Improvements in Electric Time-Locks; and we do hereby declare the following to be a full, clear, and exact description of the invention, such 10 as will enable others skilled in the art to which it pertains to make and use the same, reference being had to the accompanying drawings, which form a part of this specification.

Our invention relates to an improved electrical time-lock for safes; and it consists in a locking-bolt, a means for operating the same, an electrical operating device for facilitating or aiding the clock-movement in operating the bolt, and a device whereby the bolt may 20 be operated from the outside of the door, together with certain details of construction and combination of parts, as will be fully set forth hereinafter.

In the accompanying drawings, Figure 1 is 25 an inside face view of a safe-door provided with our improved time-lock. Fig. 2 is a front elevation of an ordinary clock-movement having the dial removed therefrom and showing our improvements attached thereto. Fig. 3 30 is a front view or elevation of the magnets and their attachments used for operating the bolting mechanism. Fig. 4 is a rear elevation of the same. Fig. 5 is a sectional side elevation of the contacts for opening the lock from the outside of the door. Fig. 6 is an enlarged 35 side elevation of the spring-connecting crank-bar and clock-movement for operating the same. Fig. 7 is a plan view of the same having the spring removed therefrom. Fig. 8 is 40 an enlarged side elevation of the central clock or hour post, showing the pointer-ratchet and hour-wheel in section. Fig. 9 is a detail view of the insulated pin and battery to be used in connection with the two contact-plates and 45 the circuit for closing the same from the outside of a safe-door should the devices get out of order.

To put our invention into practice with the lock of a safe-door A, such as are now in common use, and consisting of three horizontally and two vertically moving bolts 1, attached

together by a bar 2 and suitable cranks 3 and moving in proper bearings 4, and opened and closed by means of a handle located outside the door in a manner well known to the art, 55 we provide a clock-movement and attach the same in a suitable position on the inner side of the door A. This clock-movement is provided with a graduated dial 5 and a single hour hand or pointer 6. At the rear of 60 the central bolt 1 is pivoted in a suitable bearing 57 a locking-crank 7, one end of which is adapted to be moved and occupy a position at the rear of the said central bolt 1, and the other extremity projecting upward and attached to a draw-bar 8, located at the rear of the clock-movement and connected to an independent movement arranged and attached at the left side of the clock. This bar 8 is divided and one portion moving within the 70 other, whereby the length of the bar 8 may be increased or diminished without interfering with the position of either the crank 9 or locking-crank 7. A suitable coil-spring 11, bearing against a rigid collar 12, formed on 75 one section of the said bar 8 and against a loose collar 13 and pin 14, passed through the other section, and operating in a slot 15, formed in the bar 8, serves to keep the said bar 8 the desired length to properly operate the locking-crank 7. Attached to the shaft or spindle 47, to which the crank 9 is affixed, is a strong flat coil-spring 16, which, in connection with a ratchet-wheel 17 and several other toothed wheels 18 and intermediate pinions 19, serves as a means or power to withdraw the locking-crank 7 from the rear of the central bolt 1. The object of the several gear-wheels 18 and pinions 19 is to give a rapid rotary movement to a small disk 80 20, having a series of outwardly-projecting pins 21, which operate against a pivoted lever 22 and prevent any movement of the crank 7 until the lever is released by the clock. This lever 22 projects upward and is within reach 85 of a ratchet-crank 24, having an outwardly-projecting pin 25 secured therein. The arrangement of the hour-wheel 26 on the central shaft 55 of the clock-movement may be seen by reference to Fig. 8 on the drawings. The hour-wheel 26 is provided with an elongated hub 27, on which the ratchet crank- 90 95 100

wheel 24 is attached, which is also provided with a similar hub 28, on which the hour hand or pointer 6 is secured. These several parts all move together and may be operated by a 5 suitable key placed on the square end of the driving-shaft 55. Beneath and to one side of this clock-movement is arranged a pair of magnets 29, suitably connected together and attached to the frame 30 of the movement.

- 10 Pivoted to the pin 31, to which the lever 22 is attached, is an armature 32, which, together with the said lever, is rigidly secured to the pin 31, in order that the two may operate together. Secured to this armature 32 is a rear- 15 wardly-extending pin 33, provided with a hooked end, to which is attached a small spiral spring 34, the other extremity of which is connected to a portion of the frame 35 in a manner that will keep the armature 32 away 20 from the magnets 29 and the lever 22 in the proper position to engage with its operating-pin 21. Beneath the magnets 29 and insulated 37 from the frame 35 of the same is a small contact-bar 38, which may be adjusted 25 by means of a screw-thread formed thereon. Operating in conjunction with this bar 38 is a flexible contact 39, which is secured to one side of the armature 32 in a manner that when the said armature 32 is partly moved 30 toward the magnets 29 the flexible piece 39 will be in contact with the bar 38, and thereby complete a circuit through the magnets 29, which will be more fully set forth hereinafter.

Near the top of the clock-movement and 35 attached to the frame 30 of the same is a bracket 40, properly insulated and provided with two binding-posts 41. Near this bracket 40 is located a spring-contact 42, which is insulated 43 from the clock-movement and 40 electrically connected by a wire 44 to one of the binding-posts 41. The lower extremity of this spring-contact 42 is adapted to be placed in and out of contact with a small circular piece 45, attached to the main stem 47 45 of the secondary clock-movement in a manner that when this said movement is wound the spring 42 will be in contact, and when the tension is taken off the said movement the spring 42 will be out of contact. This circular contact 45 is provided with an over- 50 hanging flange 46, which extends partly about its periphery, and when the movement is in one position the same is out of reach of the spring 42, and when wound or turned to the right the extremity of the spring rides on the top of the flange 46, thereby forming a contact.

Located at any desired point on the inner 55 side of the safe-door are two contacts 48, the one slightly separated from the other in a manner that a small circular metallic pin placed between the same will complete or form an electrical connection between the two. The upper contact 48 is connected by a wire 49 to one of the magnets 29, and the lower contact 48 by a wire 50 to the other magnet.

In Fig. 9 of the drawings I have illustrated

means for closing the circuit from the outside of the safe-door, which consists of an insulated pin 60, a battery 61, and connections 62 70 62' intermediate between the pin and the battery. The pin 60 is constructed in two longitudinal metallic parts, which are insulated from each other by a longitudinal central insulating material 63, which extends from end 75 to end of said pin, and the outer surface of the pin has a suitable insulating-covering 64, while the inner ends of the sections of the pin are enlarged somewhat, as shown. After a hole has been bored or cut in the safe-door 80 at a point between the two contact-plates 48 85 48, the enlarged end of the insulated pin is inserted into said opening and it is caused to fit snugly between and against the two contacts 48, and to one section of the pin the wire 85 62 is secured and to the other section of the pin the wire 62' is connected, both wires leading thence to the battery 61. A complete circuit is thus formed, commencing at the battery 61, then through the wire 62 to one section 90 of the insulated pin, one contact 48, the wire 49, the magnets 29, through the wire 50, the other contact 48, the other section of the insulated pin, the wire 62', and thence back to the battery 61. This last-described circuit 95 is for the purpose of opening the lock from the outside of the door, which may be accomplished by knowing the exact location of the opening between the two contacts 48 and then drilling a hole with suitable tools 100 in the exact position and using a battery and making a contact of the two poles of the same with the two contacts 48. This circuit is only used in case the clock mechanism becomes out of order and refuses to 105 operate. After the safe has been opened in this manner, the hole or opening made in the door is plugged and the contacts 48 removed to some other position, which may be known to one or more persons.

At a suitable position on the inside of the door is located a battery for operating the circuit which aids the clock-movement to remove the locking-crank 7 from the rear of the central bolt 1. Connected in this circuit 115 110 is a single-stroke bell 52, to give notice when the door may be opened. This bell 52 only rings when the circuit is complete.

To complete the above circuit from the battery to the magnets 29, a wire 53 is connected 120 to the said battery 51 with one of the binding-posts 41, and from thence by a wire 52 to one of the contact-plates 48, and from this point by a wire 49 to one of the magnets 29, through the magnets 29 by a wire 50 to the 125 other contact-plate 48, from this point by a wire 54 to the bar 38, and thence to the spring-contact 39, secured to the armature 32, through the armature 32 to the lever 22, from the lever 22 into the clock-movement to the circular contact 45, thence through the spring-contact 42 to the wire 44 to the other binding-post 41, and from this point by means of a wire back to the battery 57.

In operation a key is secured to the stem 47 of the secondary movement for operating the locking-crank 7 and the same revolved to wind the spring 16 and thereby force the

5 crank 9 into position at the rear of the central bolt 1. These bolts 1, when the door is open, are all moved by means of the outside handle inwardly and the locking-crank 7, resting on the top of the central bolt 1, the bar 8 being permitted to contract in length by its peculiar construction. The door is now closed and the handle turned to shoot the bolts into the door-frame, which permits the locking-crank 7 to snap behind the central bolt 1,

10 15 which locks the door, which can then be opened at a certain hour by the clock-movement.

In order to have the lock open in a given number of hours, the hand or pointer 6 is 20 simply revolved until the same points or indicates that number on the face or dial 5. The pointer 6 being in a direct line with the ratchet-crank 24, or so arranged that when the pointer 6 indicates the last hour on the 25 dial, the small pin 25, secured in the ratchet-crank 24, will engage with the lever 22, move the same about its pivotal point a short distance, thereby moving the armature 32 toward the magnets 29 until the spring 39 is in

30 contact with the bar 38 and a circuit is completed. When this circuit is made, the magnets attract the armature 32 and release the disk 20, which is held stationary by one of its pins 21, engaging with a projection 56, 35 formed on the lever 22, thereby releasing the secondary movement, which draws the crank 9 back, and by means of its connecting-bar 8 revolves the locking-crank 7 upward, thereby releasing the bolts 1, and the safe-door is 40 opened by the handle. At the moment the circuit for releasing the secondary movement has been completed the alarm-bell 52 gives one tap to warn the cashier or others that the door may be opened.

45 When the locking-crank is in a position, as shown at Fig. 2 on the drawings the circuit is broken, as the circular contact 45 has revolved beyond the reach of the spring 42, which releases the armature 32 and permits 50 the lever 22 to again engage with the pins 21 of the disk 20 and resume its former position by the action of the small spiral spring 34.

Having thus described our invention, what we claim, and desire to secure by Letters Patent, is—

55 1. In a time-lock for safe-doors, the combination consisting of the locking-crank 7, a divided bar 8, actuated by a spring 11 and connected to a crank 9 of a secondary movement, and a means for releasing the said movement at a given time, as and for the purpose set forth.

60 65 2. In combination with a time locking device operated by an electrical circuit, an open branch circuit provided with contact-plates separated the one from the other and located at a suitable point on the inner side of the

door, whereby a contact or connection may be made between the two by perforating the door at that point, as and for the purpose described.

3. In a time-lock, the combination, with the bolt-works, of a locking-crank adapted to be thrown or adjusted into the path of said bolt-works to arrest the withdrawal of the same, 70 an extensible rod connected to said locking-crank, a secondary clock-work connected to said extensible rod and having the stop-wheel 20, a primary time mechanism having its hand-arbor provided with the arm 24, an electrical circuit including the magnets 29, the contacts, and the armature for the purpose of closing said circuit and a lever 56, which normally engages the stop-wheel 20 to arrest the secondary clock mechanism and which 75 carries an armature to be attracted by the magnets, said lever being arranged in the path of the arm 24 of the primary time mechanism and adapted to be operated by said arm at the proper period of time to close the 80 circuit through the armature and release the stop-wheel 20, whereby the secondary time mechanism is released to retract the extensible rod and withdraw the locking-crank out of the path of the bolt-works, substantially 85 as described.

4. In a time-lock, the combination, with the bolt-works, of a locking-crank, a secondary clock-work, an extensible spring-controlled rod connected to said locking-crank and to 100 the secondary clock-work to be operated by the latter, an open electrical circuit, the magnets included in said circuit, a primary time mechanism having its hand-arbor provided with an arm, and a lever 22, arranged in the 105 path of the arm of the primary time mechanism and carrying an armature and contact-piece to close the electric circuit through said magnets and armature, whereby the secondary clock-work is released from the lever and 110 operates to retract the extensible rod and the locking-crank, substantially as described.

5. In a time-lock, the combination, with the bolt-works, of a locking-crank, a secondary clock-work having the stop-wheel 20 and the 115 rotatory contact 45, a rod 8, connected to the locking-crank and to the clock-work, an open electrical circuit, the magnets included in said circuit and having the yielding contact which presses against the rotary contact 45 120 of the secondary clock-work, a primary time mechanism having the arm, and a lever 22, held in the path of the arm of said primary time mechanism and carrying an armature, for the purpose described, substantially as 125 set forth.

6. In a time-lock, the combination, with the bolt-works, of a pivoted locking-crank, a secondary clock-work having the stop-disk 20, the rod 8, connected to the locking-crank and 130 to the secondary clock-work and having the extensible sections and the retracting-spring, the open electrical circuit, the magnets included in said circuit, the primary time mech-

anism having the arm 24, the lever normally engaging the stop-wheel of the secondary clock-work and arranged in the path of the arms of said primary time mechanism, and 5 the armature and contact-piece carried by the lever and adapted to close the circuit when attracted by the magnets, for the purpose described, substantially as set forth.

7. In a time-lock, the combination, with the 10 bolt-works, of a locking-crank, a secondary clock-work having the stop-wheel 20, the rod intermediate of the locking-crank and the secondary clock-work, the open electrical circuit, the magnets included in said circuit, 15 the spaced electrical contacts 48, included in said circuit and adapted to be closed by insertion of a pin between said plates, the le-

ver 22, normally engaging the stop-wheel 20 and carrying an armature and the yielding electrical contact 39, the contact-bar 38, arranged in the path of the said yielding contact 39, and the primary time mechanism having the arm arranged to move the lever 22 out of engagement with the stop-wheel 20, substantially as described. 25

In testimony that we claim the foregoing we hereunto affix our signatures this 2d day of April, A. D. 1890.
